UNITED STATES PATENT OFFICE.

WILLIAM F. WAIT, OF AUBURN, NEW YORK, ASSIGNOR TO LORENZO W. NYE
AND WILLIAM F. WAIT, OF SAME PLACE.

DESIGN FOR CARPET.

Specification forming part of Design No. 7,482, dated June 2, 1874; application filed May 13, 1874.
[Term of Patent 3½ years.]

To all whom it may concern:

Be it known that I, WILLIAM F. WAIT, of the city of Auburn, and county of Cayuga, State of New York, have invented and produced a new and original Design for Carpets, of which the following is a specification:

The nature of my design is fully represented in the accompanying photographic illustration, to which reference is made.

I claim as my invention—
The configuration of the design hereunto annexed, when applied to carpeting.

WILLIAM F. WAIT.
